UNITED STATES PATENT OFFICE.

ERNEST ALWIN VETTER, OF BROOKLYN, NEW YORK.

HAIR CLIPPER.

Application filed January 15, 1924. Serial No. 686,412.

To all whom it may concern:

Be it known that I, ERNEST A. VETTER, a citizen of the United States, and a resident of the city of New York, borough of Brooklyn, in the county of Kings and State of New York, have invented a new and Improved Hair Clipper, of which the following is a full, clear, and exact description.

This invention has relation to hair clipping devices and has particular reference to hair clippers of the reciprocating knife type.

One of the outstanding objects of the present invention is to provide a clipping device in which the operating handles are so associated therewith as to dispose the same in laterally projecting relation to the cutters whereby the clippers may be used by a person in the operation of cutting or clipping his own hair.

As a further object the invention contemplates a hair cutting device in which the operating handles are detachably and reversibly associated with the cutting elements or knives to permit of their reversal and use with either hand.

As a still further object the invention aims to provide a hair clipping device which is comparatively simple in its construction and mode of operation, which is inexpensive to manufacture and produce, and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a perspective view of a hair clipper constructed in accordance with the invention.

Fig. 2 is a plan view of the operating handles removed from the cutting elements.

Fig. 3 is a diagrammatic plan view illustrating the manner in which the operating handles may be reversed.

Referring to the drawings by characters of reference, 10 and 11 designate respectively a pair of blades each having a plurality of cutting teeth 12 at one edge thereof. The

blade 11 which will be hereinafter termed the movable blade is superimposed on the blade 10 which will be hereinafter termed the stationary blade and is connected with said stationary blade for reciprocation whereby the cutting teeth coact to set up a shearing action for clipping or cutting the hair. As illustrated, the stationary blade 10 is provided with a central upstanding

shaft or trunnion 13 which extends through a longitudinal slot in the movable blade 11 and which is threaded for a purpose to be hereinafter disclosed. The upper face of the

blade 11 is longitudinally grooved as at 14 to receive therein the downturned guide

flange 15 at the forward edge of the retaining and guiding plate 16 which overlies the

blade 11. The rear edge of the plate 16 is provided with depending feet 17 which are

received in the notches at the rear edge of the stationary blade 10. The trunnion or threaded shaft 13 projects through a central opening in the plate 16 and receives

thereon an adjusting nut 19 between which and the plate a bowed leaf spring 20 is interposed for exerting a pressure on the plate

16 whereby its flange 15 in turn serves to impinge the blade 11 against the blade 10.

By turning the nut 19 in opposite directions the pressure may be increased or decreased to obtain the best results from the clipper.

The nut 19 is provided with a reduced upwardly projecting annular boss 21 and the

plate 16 is provided with a pair of upwardly projecting eccentric trunnions 22 and 23 adjacent its rear edge and equidistantly spaced from the boss 21. The movable

blade 11 is further provided with a rearwardly projecting ear 24 having a bearing

aperture 25 extending vertically therethrough. A pair of manipulating handles

26 and 27 are pivotally connected at one end by a pivot sleeve 28 and are formed at their

opposite free ends with finger receiving

loops 29. The handle 27 which will be hereinafter termed the stationary handle has

secured thereto adjacent its free end a leaf spring 30 which spring bears at its free end against the movable member 26 at a point adjacent the pivoted end thereof whereby the free ends of the handles are normally swung apart. A stop lug 31 is provided on the stationary handle member for limiting

the relative separation or opening movement of the handle members.

The internal diameter of the pivot sleeve

28 is of a size to snugly fit over the boss 21 and the stationary handle member is further provided with an aperture 32 which is appropriately spaced from the pivot sleeve 28 5 to engage over either of the eccentric trunnions 22 or 23 whereby the stationary handle member is coupled to the stationary blade 10 against relative movement with respect thereto. The movable handle member 26 10 is provided with a lateral extension 33 at its pivoted end, which lateral extension is formed with a head 34 having oppositely projecting vertical lugs 35 and 36 which are adapted to respectively engage with the 15 bearing aperture 25 in the ear 24 when the handle members are reversibly associated with the clipper blades. Under this construction it is obvious that when the handle members are operatively associated with 20 the clipper blades they project from the sides thereof so that the cutting teeth protrude at a right angle to the length of the handle members, thus facilitating the use 25 of the device in the operation of a person cutting his own hair. In order to provide means for retaining the handle members in associated relation with the clipping blades, a retaining knurled nut 37 is threaded upon the free end of the threaded shaft or trunnion 30 13.

In use and operation, the handle members are associated with the blades by engaging the pivot sleeve 28 over the boss 21 and simultaneously engaging the aperture 32 in the stationary handle member 27 over the eccentric trunnion 23 with the depending vertical lug 36 engaging in the bearing aperture 25 of the ear 24. The nut 37 is then threaded in place. The operator inserting the finger and thumb of the right hand in the loops 29 may then conveniently operate the device to clip upwardly at the back of the head. The relative opening and closing movement of the handle members 40 will effect through the engagement of the lug 36 and the bearing aperture 25 of the ear 24 relative reciprocation of the blade 11 and its teeth 12 with respect to the blade 10 and its teeth 12 whereby the shearing and cutting action is effected. When it is desired to clip upwardly with the left hand, the retaining nut 37 is removed and the handle members arranged in reverse relation by engaging the aperture 32 over the eccentric trunnion 22 with the lug 35 and the bearing aperture 25 of the ear 24, it, of course, being understood that the pivot sleeve is also engaged over the boss 21 and the nut 37 replaced.

From the foregoing it will thus be seen 60 that a clipping device has been provided in which the operating handle members are capable of detachable and reversible association with the blades and protruding from the sides thereof in order to afford means

which permits of the use of clippers in the operation of cutting one's own hair.

I claim:

1. In a hair clipping device a stationary blade and a movable blade each having cutting teeth, the movable blade having a slot, a threaded concentric stud on the stationary blade extending through the slot in the movable blade and having means for preventing relative separation thereof while permitting of reciprocatory movement therebetween, and means for actuating the said blades comprising an apertured ear carried by the movable blade, a pair of eccentric trunnions projecting upwardly from the stationary blade, a pair of pivotally connected operating handles having an aperture at their pivotal point for engaging over the threaded stud, oppositely projecting lugs on one of the handles selectively engageable in the apertured lug, the opposite handle member having an opening selectively engageable with the eccentric trunnions and a nut for engagement on the threaded stud to retain the handles in place, whereby said handles are capable of operative connection with the blades to dispose the same in a position projecting from either end thereof.

2. The combination with a hair clipper which includes a pair of blades each having cutting teeth at one edge and connected for relative reciprocatory movement, of a pair of pivotally connected handle members for actuating the blades, interengageable means formed respectively on said blades and handle members to permit of reversible and operative connection therebetween, said means consisting of an apertured portion at the pivotal point of the handle members, an apertured portion in one of the handle members, a central trunnion carried by one of the blades for receiving the apertured portion at the pivotal point thereof, a pair of eccentric trunnions carried by the said blade and adapted to respectively receive the apertured portion of said handle member upon reversal thereof, an apertured ear formed on the other blade, and oppositely projecting lugs on the remaining handle member adapted to respectively engage with the apertured ear upon reversal of the handle members.

3. In a hair clipping device comprising stationary and movable clipping blades each provided with cutting teeth at one edge adapted to coact upon reciprocation of the movable blade with respect to the stationary blade, of detachable and reversible actuating means therefor comprising a pair of pivotally connected stationary and movable handle members having a bearing aperture at their pivotal point, a central trunnion carried by the stationary blade for receiving said bearing aperture, an apertured portion in the stationary handle member, a pair

of eccentric trunnions carried by the stationary blade adapted to respectively receive the apertured portion of the stationary handle member upon reversal of the same, 5 an operating ear carried by the movable blade having a bearing aperture, and eccentric oppositely projecting axial lugs carried by the pivoted end of the movable handle member for respectively engaging therewith 10 upon reversal of the handle members.

4. In a hair clipping device comprising stationary and movable clipping blades each provided with cutting teeth at one edge adapted to coact upon reciprocation of the 15 movable blade with respect to the stationary blade, of detachable and reversible actuating means therefor comprising a pair of pivotally connected stationary and movable handle members having a bearing aperture 20 at their pivotal point, a central trunnion

carried by the stationary blade for receiving said bearing aperture, an apertured portion in the stationary handle member, a pair of eccentric trunnions carried by the stationary blade adapted to respectively receive the 25 apertured portion of the stationary handle member upon reversal of the same, an operating ear carried by the movable blade having a bearing aperture, eccentric oppositely projecting axial lugs carried by the 30 pivoted end of the movable handle member for respectively engaging therewith upon reversal of the handle members, means carried by the stationary handle member and engageable with the movable handle member 35 for normally effecting relative separation of the free ends thereof, and means carried by the stationary handle member for limiting said separating movement.

ERNEST ALWIN VETTER.
